Attn:

UNITED STATES PATENT OFFICE.

FRANCIS H. BUZZACOTT, OF CHICAGO, ILLINOIS.

DESIGN FOR A HAIR-CLASP.

SPECIFICATION forming part of Design No. 34,093, dated February 19, 1901.

Application filed January 14, 1901. Serial No. 43,292. Term of patent 7 years.

To all whom it may concern:

Be it known that I, FRANCIS H. BUZZACOTT, residing at No. 1325 Seventy-fourth street, Chicago, county of Cook, and State of Illinois, have invented and produced a new and original Design for a Hair-Clasp; and I hereby declare the following to be a full, clear, and exact description thereof, reference being made to the accompanying drawings, forming a part thereof.

In the drawings, Figure 1 is a view in side elevation of a hair-clasp of my new and original design, and Fig. 2 a sectional view taken as indicated at line 2 of Fig. 1.

As shown in the drawings, the leading or material feature of my design consists in a

coil A, having its convolutions lying comparatively close to each other, an eye B, secured to one end of the coil and projecting laterally on one side thereof, and a hook C, secured to the other end of the coil and projecting laterally therefrom in the same direction as does the eye B.

What I claim as new, and desire to secure by Letters Patent, is—

The design for a hair-clasp herein shown and described.

FRANCIS H. BUZZACOTT.

In presence of—

D. W. LEE,
ALBERT D. BACCI.
